UNITED STATES PATENT OFFICE.

WILLIAM G. COUGHLIN, OF PHILADELPHIA, PENNSYLVANIA.

RAIL-CHAIR.

1,260,151.

Specification of Letters Patent. Patented Mar. 19, 1918.

Application filed September 23, 1916. Serial No. 121,823.

To all whom it may concern:

Be it known that I, WILLIAM G. COUGHLIN, a citizen of the United States, and resident of Philadelphia, county of Philadelphia, and State of Pennsylvania, have invented certain new and useful Improvements in Rail-Chairs, of which the following is a specification.

- This invention relates to an improvement 10 in rail chairs and more particularly to chairs adapted for sustaining double headed rails or rails which have two wearing surfaces and are capable of being reversed. One object of the invention is to provide a rail 15 chair which will permit of an adjustment of the rail toward the center of the track to compensate for the wearing of the inner face of the head of the rail by the flanges of the car wheels.
- Another object is to provide a chair which 20 will protect the tie and afford maximum security in supporting the rail with a minimum of metal.

The invention will be described in connection with the accompanying drawing, in 25 which,

Figure 1 is a sectional view of a double headed rail with one form of the improved rail chair;

Figs. 2 and 3 are like views of different 30 forms of chairs embodying the invention; and

Fig. 4 is a side view of a rail showing one 35 of the chairs as applied to a single tie and another chair spanning two ties and supporting a rail joint.

Rail chairs embodying the present invention may be used on single ties or in more elongated form they may serve as "splice bars" to connect the abutting ends of the rails and to support the rails. In each of the figures of the drawing R indicates the rail which is preferably formed with two heads 10 and a connecting web 11. The 40 heads of the rail are of the usual form having the inclined under surfaces 12. The web of the rail is formed with diverging inclines 13 adjacent each head and an intervening web which is perforated to receive the bolts 14. As shown in the drawing the 45 perforations for the bolts are centrally arranged between the heads of the rail so that the same bolt holes will answer with either head of the rail uppermost.

Referring to Fig. 1, the chair C comprises 50 a base 15 and two upwardly and inwardly

inclined web members 16, 16^a. The web members have angular feet 17 having horizontal portions 18 which rest on the flat central part of the base and outwardly directed upwardly inclined portions 19 which rest on the corresponding inclines of the base. These feet are thus seated securely in the angles of the base but to prevent possibility of spreading the base is provided with 60 toes 20 against which the feet of the chair members abut and bolts 21 are also preferably provided to securely connect the chair members to the base. The upper part of each web 16 is provided with a vertical surface 22 to form an abutment for the bolt and nut and with inclines 23, 24, to abut against the inclines 12 and 13 of the rail respectively. In order that these pairs of inclines 65 may be securely seated against each other 70 a recess 25 is formed in each chair member between the inclines 23, 24. It will be evident that when the bolts 14 are tightened the inclines 23, 24 fit the inclines 12, 13 with 75 a wedging action which will hold the rail 80 very securely in the chairs.

The web member 16^a is slightly higher than the web member 16, which tends to throw the head of the rail slightly to the left of the center line of the chair. In installing a new rail the higher web member 16^a is placed at the inner side of the rail or 85 toward the middle of the track. When the corresponding side of the rail head becomes worn the rail may be reversed, end for end, 90 thus permitting the other side of the rail head to take the wear of the wheel flanges. When both sides of the rail are worn the chair members may be reversed, placing the higher member 16^a on the outside of the rail 95 and the lower member 16 on the inside. This will throw the head of the rail toward the inside of the track slightly to compensate for wear and after the inner side of the head of the rail becomes again worn sufficiently to require change the rail may be again reversed end for end and the other side of the head subjected to the wear of the wheel flanges. When one head of the rail becomes sufficiently worn to be useless the 100 rail is reversed to bring the other head into operative position. It will thus appear with my improved rail chair the rail may be not only reversed to place either head uppermost but it may be reversed end for end and adjusted laterally to compensate for wear, by 105 reason of which adjustments a double head-

ed rail will last longer than two single headed T-rails, while the additional strength of the double head rail is in itself a great advantage over the T-rail.

- 5 In the forms illustrated in Figs. 2 and 3 the side or web members of the chair C are adjustable on the base to permit of adjusting the rail toward the center of the track to take up wear upon the rail head without disturbing the base on the tie. It will be understood that in all the forms, notches or holes are provided in the edges of the chair bases to receive spikes 26 and that it is desirable to have the bases permanently located on the ties. Referring to Fig. 2, the base 30 is substantially flat and provided with serrations or notches 31 on its upper side. The two side members of the chair 32, 32^a have feet 33 provided with teeth which are complementary to the notches in the base. These feet 33 are secured to the base by means of bolts 34, the bolts passing through slots or notches in the feet which permit of adjustment of the feet relatively to the base. 25 The inner walls of the slots are indicated by the dotted lines 35.

At the outer side of the rail, that is, the side away from the center of the track, the side member 32^a is provided with a shoulder 36 which fits the under side of the rail head and supports the rail and with a stout flange 37 which fits against the outside of the rail head and supports it against the lateral thrust of the wheel flange. The upper portion of the inner side member 32 is preferably constructed in the same form as the corresponding portion of the side member 16 in Fig. 1 and I have applied the same reference characters thereto.

- 40 Fig. 3 illustrates a form of the invention which differs from that shown in Fig. 2 only in the substitution of vertical teeth 37, 38, somewhat similar to gear teeth, on the base plate and in the feet of the side members of the chair. In the forms shown in Figs. 2 and 3, as in Fig. 1, the side members of the chair are rigidly connected together and to the rail by bolts 14 which preferably pass centrally through the rail 45 so that the same holes in the rail will suffice with either head of the rail uppermost. In the form shown in Figs. 2 and 3 the rail may be reversed to bring either head into the upper operative position and it may be turned end for end to bring either side of the rail toward the inside of the track to take the wear of the wheel flanges. Furthermore, each side of each head may be adjusted toward the center of the track to take 55 up wear by loosening the bolts 34 and adjusting the side members of the chair into new notches in the base after which adjustment the bolts 34 are again screwed up tight.

60 65 It will be understood that the construc-

tion shown in Figs. 1, 2 and 3 may be used as simple rail chairs, as shown at the right in Fig. 4, or, in more elongated form they may be made to span two or more ties and to support the rail joints, as shown at the left in Fig. 4. In other words, these constructions are equally suitable for rail splices and rail chairs and it will be understood that the term "chair" as used herein is intended to include rail supports used either as ordinary chairs or as splice bars.

It will also be understood that the rail chairs above described may be used with rails having a single head and a depending web, although double head rails are preferable.

Having described the invention what is claimed is:—

1. The combination with a rail comprising a head having bearing surfaces underneath its opposite sides terminating in a downwardly projecting central web, of a rail support comprising a horizontal base and two upwardly converging web members, the web members having supporting surfaces to coöperate with the rail bearing surfaces and said supporting surfaces being at different elevations whereby the head of the rail may be adjusted laterally with respect to the base to take up wear by reversing the supports.

2. The combination with a rail comprising a head having bearing surfaces underneath its opposite sides terminating in a downwardly projecting central web, of a rail support comprising a horizontal base and two upwardly converging web members, means for clamping the web members to the rail, and means for removably securing the web members to the base, one of the web members having a rail supporting surface higher than the rail supporting surface of the other member, and said web members being interchangeable, for the purpose set forth.

3. The combination with a rail comprising a head having downwardly converging bearing surfaces underneath and a web having upwardly converging bearing surfaces, of a chair comprising a base and upwardly converging web members, said web members having inclined surfaces conforming to the inclines of the head and web of the rail, and having feet adjustably secured to the base member.

4. The combination with a rail comprising a head having downwardly converging bearing surfaces underneath and a web having upwardly converging bearing surfaces, of a chair comprising a base and upwardly converging web members, said web members having inclined surfaces conforming to the inclines of the head and web of the rail, said web members supporting the rail and one of said web members having in-

clines conforming to the inclines of the rail, and a recess between said inclines, and means for securing said web members to the rail and for adjustably securing said 5 web members to the base.

5. The combination with a rail having two heads and an intervening web, the inner surfaces of the heads and the adjacent surfaces of the web converging toward each 10 other, of a chair comprising a base and two upwardly and inwardly converging web members, the upper parts of said web mem-

bers being constructed to conform to the inclines of the rail and the lower parts of said web members being adjustably seated on 15 the base and provided with means for securing them on the base, whereby the rail may be used with either head uppermost and whereby its operative head may be adjusted bodily laterally with respect to the base, for 20 the purpose set forth.

In testimony whereof I affix my signature.

WILLIAM G. COUGHLIN.
